[57] **ABSTRACT**

A sonic-pulse-producing assembly for use in underwater echo ranging which comprises

- a. a linear charge of detonating explosive arrayed in the form of a helix having a uniform pitch, P, which satisfies the relationship

$$P \leq 0.75 \times C/D \times L$$

where D is the detonation velocity of said explosive, L is the length of explosive in each turn of said helix, and C is the velocity of sound in sea water, said linear charge being so arrayed that the closest approach of explosive in successive turns of said helix is no less than the minimum cross-sectional dimension of said linear charge;

- b. supporting means adapted to maintain said explosive in said helical array; and
c. an initiator in initiating relationship to one end of said explosive, said initiator being adapted to be actuated by a self-contained actuating means when said assembly is at a predetermined depth in the ocean.

EXPLOSIVE ECHO RANGING DEVICE

The present application is a continuation-in-part of our prior application Ser. No. 13,385, filed Mar. 7, 1960, now abandoned.

The present invention relates to an improved device for echo ranging. More particularly, this invention relates to an explosive sonic source emitting a sequence of pressure pulses having a predetermined Doppler character.

The acoustic detection of submarines is based on the transmission of sound from the submarine to the detector element located in the ocean area in which the submarine is operating. The sound emanating from the submarine can be either noise generated internally within the submarine, noise caused by the submarine passing through the water, or sound (echoes) reflected by the submarine from nonconnected sound sources in the ocean. Active acoustic systems, which use nonconnected sound sources, are particularly useful for detecting quiet submarines.

The sonic sources generally employed for underwater echo ranging are electromechanical transducers and explosives. Explosives are more advantageous in several respects: (1) they generate a high-energy acoustic signal in useful frequency bands and thus are effective over long distances; (2) they can be placed conveniently at great depths in the ocean where the troublesome effects of refraction on sound transmission to the target are minimized; and (3) because of their light weight and independence of electrical power sources, they are suitable for launching from fixed-wing aircraft.

The explosive charge which has heretofore been employed in echo ranging is a point charge which emits a single pulse of acoustic energy when detonated. This acoustic source is used in combination with an omnidirectional hydrophone as the acoustic receiver. The useful detection range of such a system is limited primarily by reverberation (i.e., the reflected and scattered energy received from the bottom, surface, and volume of the ocean) because the sound generated by detonation of the charge is radiated with equal intensity in all directions. The acoustic energy reflected and scattered from the ocean surface and bottom toward the hydrophone will often obscure the energy (echo) reflected from a submarine at ranges which equal or exceed the ocean depth.

An explosive charge in the form of a line, a so-called "line charge" is being introduced for use in explosive echo ranging systems to provide some control over the direction in which the major portion of the acoustic energy is emitted by an explosive charge and thereby to reduce the reverberation problem. Like the point charge, the line charge also emits a single pulse of acoustic energy. However, when a line charge is oriented vertically in the ocean and detonation is initiated at the bottom end, most of the energy is emitted in an acoustic beam with its axis about 13° above the horizontal. The form of this beam pattern depends upon the length of the line charge, longer charges giving narrower beams, and lower vertical side lobe levels. The narrow beam and low vertical side lobe level from a long line charge mean that less energy is radiated toward the ocean surface and bottom especially in the near vertical direction from the charge. Thus, if a submarine lies in the path of the beam from a line charge, there will be less acoustic energy scattered back from the surface and bottom and therefore there will be less undesirable interference with the echo of the submarine than in the point charge case. An obvious disadvantage of the narrower beam is that the submarine must lie in a relatively small volume of ocean if it is to be detected; another disadvantage is that the sound is scattered by ocean surfaces at about the same range and elevation angle as the submarine target. If the single beam lobe of the line charge is too narrow, the probability of finding a submarine will be less.

Thus, point charges and line charges are of limited use for echo ranging because of the reverberation problem with point charges, and the decreased probability of finding a target within the narrow beam from line charges which are sufficiently long to suppress the reverberation.

The present invention provides a novel explosive sonic source free of the disadvantages associated with conventional explosive sound sources, the sonic source of this invention emitting narrow acoustic beams, each of a different character in each of a wide variety of directions.

The echo ranging device of this invention is an assembly for producing a sequence of sonic pulses which comprises (a) a linear charge of detonating explosive arrayed in the form of a helix having a uniform pitch, P , which satisfies the relationship

$$P \leq 0.75 \times \frac{C}{D} \times L$$

where D is the detonation velocity of said explosive, L is the length of explosive in each turn of said helix, and C is the velocity of sound in sea water, said linear charge being so arrayed that the closest approach of explosive in successive turns is no less than the minimum cross-sectional dimension of said linear charge; (b) supporting means adapted to maintain said explosive in said helical array; and (c) an initiator in initiating relationship to one end of said explosive, said initiator being adapted to be actuated by a self-contained actuating means when said assembly is at a predetermined depth in the ocean. The linear explosive charge can be arrayed in extended fashion to form the helical turns as, for example, by taking a length of explosive cord or tape, extended to form essentially a straight line, and wrapping the extended cord or tape to form a helix. Alternatively, the linear charge can be arrayed in contracted fashion to form the helical turns as, for example, by bending an explosive cord or tape to form a zigzag, and wrapping the thus contracted cord or tape to form a helix. Whether the linear charge is extended or contracted, no segment of the charge in any helical turn approaches its corresponding segments in adjacent turns by a distance less than the minimum cross-sectional dimension of the linear charge, i.e., the diameter of a circle if a circular cord is used, or the thickness of a tape.

Because of its unique structural characteristics, the present echo ranging assembly has highly desirable acoustic properties.

40 The explosive charge of the present assembly is different from conventional charges in that it possesses all of the following properties: (1) it emits oscillatory energy, i.e., in the form of a sequence of pressure pulses, instead of a single pulse as emitted by conventional charges; (2) energy is emitted from the charge in substantially equal intensity in a wide range of directions; (3) energy is beamed from the charge in narrow frequency bands; and (4) the charge is Doppler in character, the frequency of the pulsation emitted therefrom being angular-dependent. The geometry and detonation velocity of the explosive charge in the present assembly can be chosen to provide frequencies which propagate without serious attenuation losses in the sea, and which reflect well from a submarine target. In addition, reverberation frequencies can be separated from echo frequencies because of the Doppler nature of the charge. That is, for the same echo arrival time, the frequency characteristic of an echo from a target located in the near-surface layers of the ocean will be different from those of the sound reflected from the ocean bottom. Therefore, bottom reflections can be rejected by filtering the signal. The filters may be chosen so as to pass the band of frequencies sent toward a submarine target and which will therefore also be the band of frequencies containing the energy of the echo from the target.

65 The frequency of the sound irradiating the target depends on the angle of elevation between the present assembly and the target. Therefore, the frequency of the returning echo depends upon the range and depth of the target. Since the time of arrival of the echo also depends upon the range of the target, the frequency of the returning echo also depends upon the time of arrival. Therefore, the filtering process must be time-dependent. After the echo of a target is identified, the range to the target can be determined by measurement of the time interval between emission of the pulse sequence and reception of the echo.

The manner in which the explosive charge present in the assembly of this invention provides oscillatory energy of Doppler character is explained as follows:

When the explosive charge is initiated, a continuous pressure front is created which emanates radially from the moving detonation front. For a straight linear charge, the resulting pressure front is conical in form. Because of the helical configuration, this conical pressure front is coiled up upon itself. Successive portions of this front will therefore arrive in sequence at a fixed point outside the charge. Thus, while the propagation of detonation from one end of the helical charge to the other is continuous, the helical configuration will cause the pressure pulse emitted in any direction away from and nonaxial to the helix to wax and wane as the detonation proceeds in each turn of the helix, the greatest amplitude being emitted in the chosen direction when the component of the detonation velocity in this direction is equal to the velocity of sound in water. Therefore, a pressure gauge placed at any selected position will register the arrival of pressure from successive turns of the coiled front as a succession of pressure pulses, the time interval between the arrival of the successive pulses being determined by the detonation velocity of the explosive and the length of each helical turn. Since the explosive propagates detonation at constant velocity, the time interval between the arrival of successive pulses at a selected position from the charge will be constant when the pitch and length of the helical turn are uniform throughout the length of the helix.

However, inasmuch as the helical configuration introduces an axial displacement of the coiled pressure front, the time interval between the arrival of the successive pulses will vary according to the angle of emanation from the helix. Therefore, the frequency of the pulsation will vary depending upon the angle the emanating pulses make with the axis of the helix. When this angle approaches 180° (i.e., a direction along the axis and in the general direction of the detonation in the helix) the frequency approaches the maximum level for the charge. When this angle approaches 0°, the frequency approaches the minimum for the same charge. At any angle between 180° and 0°, the wave length and frequency in the specified direction will be intermediate these values according to the angle of observation.

In order to describe the present invention more fully, reference is now made to the accompanying drawings in which

FIG. 1 is a front view of one modification of the sonic-pulse-producing assembly of the present invention;

FIG. 2 is a top view of the pulses emanating from the assembly shown in FIG. 1;

FIG. 3 is a schematic view of the pattern of pulses emanating from the assembly shown in FIG. 1;

FIG. 3A shows a series of pulse points along three different paths in the pattern shown in FIG. 3;

FIG. 4 is a schematic view of a helical explosive charge such as is employed in the present assembly;

FIGS. 4A through 4E are pressure-time plots for the pulsation arriving at points A, B, C, D, and E, respectively, of FIG. 4;

FIG. 5 is a front view of another modification of a helical explosive charge for use in the assembly of this invention;

FIG. 6 shows a series of pulse points obtained from the helical charge shown in FIG. 5;

FIG. 7 is a front view of still another modification of a helical explosive charge for use in the assembly of this invention;

FIG. 8 is a vertical-view diagram showing three targets located in the near-surface layers of the ocean and at different horizontal distances from the assembly of this invention;

FIG. 9 is a top view of the situation shown in FIG. 8;

FIG. 10 is a top view diagram of one scheme for locating a target by use of the assembly of the present invention; and

FIG. 11 is a display of data obtained after initiation of the helical explosive charge of the present assembly in the ocean.

Referring now to the drawings in greater detail in FIG. 1 a length of explosive 1 is wrapped around a hollow tube 2 made of a flexible plastic material, the explosive being wrapped in

such a way as to describe around the tube a helix having a pitch, P , which satisfies the relationship

$$P \leq 0.75 \times \frac{C}{D} \times L$$

where D is the detonation velocity of the explosive, L is the length of explosive in each helical turn, and C is the velocity of sound in sea water. The pitch of a helix can be broadly defined as the distance between helical turns measured parallel to the helical axis. However, in the present assembly since the helical turns are formed from a linear explosive charge, each helical turn has a dimension parallel to the helical axis and the points defining the pitch of the helix must be specified more precisely. To do this, the periphery of the linear explosive charge arrayed as a helix can be considered as an envelope having an upper boundary line and a lower boundary line, designated X and Y, respectively, in FIG. 1. As is shown in this figure, the pitch, P , of this helical charge is the distance, measured parallel to the helical axis, between corresponding points on the upper (or lower) boundary lines of successive turns of the helix. As is seen, the closest approach of explosive in successive turns of the helix is no less than the minimum cross-sectional dimension of the linear charge. The tube 2 is constricted at the top by means of a sheet of flexible plastic material having an aperture 7 therein, and the bottom of the tube is held open by shroud ring 6. A weight 5 hangs from shroud ring 6 by means of shrouds 4. An initiator, 3, for example, a pressure-actuated initiator, is attached to the length of explosive at the upper end thereof. The tube is kept fully inflated with water during its descent in the ocean owing to the scooping effect of the open end of the tube. Explosive 1 is initiated when the assembly reaches a depth at which the hydrostatic pressure is sufficient to actuate the initiator 3.

FIG. 2 depicts a portion of the pressure front produced by the detonation of the helical explosive charge of FIG. 1 as seen looking down on the charge. As is shown, the front is continuous and is coiled upon itself as the detonation traverses the helical configuration.

FIG. 3 depicts the plurality of pressure fronts produced by detonation of the helical explosive charge of FIG. 1 as viewed in a plane of the axis of the charge, the charge having been initiated at a and the detonation having travelled at a constant velocity through points b , c , d , e , f , g , and h . The pressure fronts, moving at constant velocity radially from the portion of the helix producing them, describe a series of eight semicircles having centers at each of the eight points, the semicircle whose center is a having the longest radius and each of the semicircles with centers at b , c , d , e , f , g , and h being consecutively shorter in radius than the immediately preceding semicircle by a constant decrement owing to the constant time interval between the detonation of each point. Because of the downward shift in the centers of the pressure fronts, the distance between fronts is at a minimum in the direction in which the detonation progresses, and increases to a maximum in the opposite direction. Consequently, three rays A, B, and C, which leave the charge at different angles therefrom, have different frequencies. A, which is emitted in a downward direction, has a higher frequency than B, which is emitted in a nearly horizontal direction from the charge; and B has a higher frequency than C, which is emitted in an upward direction from the charge.

FIG. 3A illustrates the pulse pattern produced along paths traversed by rays A, B, and C as it would be recorded by a pressure-pulse recorder.

FIGS. 4 and 4A through 4E illustrate the essentially even distribution of sonic energy in a wide range of directions from the assembly of this invention. The explosive charge 1 in FIG.

4 is initiated by initiator 3, and the acoustic signal is measured at distant points in the directions A, B, C, D, and E and at equal distances from the charge. The relative pressures of the signals at equally distant points in the directions A, B, C, D, and E are given in FIGS. 4A, 4B, 4C, 4D, and 4E, respectively. These plots show that in all non-axial directions from the as-

sembly there is an oscillatory signal. The plots also show the variation of the frequency of the pulse sequence with the angle of observation.

In FIG. 5, 1 is a length of explosive arrayed in the form of a helix, the amount of explosive per unit of length of 1 being maximum at the center portion of the length of explosive and the amount of explosive per unit of length decreasing uniformly in both directions from the portion of maximum loading. Because of the difference in explosive loading, the pulses from the helical charge of FIG. 5 assume the pattern shown in FIG. 6.

The helical charge shown in FIG. 7 is preferred for use when it is desired to emit a pulse sequence in lower frequency ranges where the longer period requires a long length of explosive per helical turn. This charge is constructed from a linear explosive 1 in the zig-zag form, and the zig-zag charge is arrayed in the form of a helix, the length of explosive in the zig-zag segment comprising a turn of helix being equal to that in all of the other turns. In considering the pitch, P , of the helix shown in FIG. 7, the zig-zag charge is considered as having an imaginary envelope formed by an upper boundary line, X, and a lower boundary line, Y, indicated by dotted lines in FIG. 7. As is shown, the pitch, P , of this helical charge is the distance, measured parallel to the helical axis, between corresponding points on the upper (or lower) boundary lines of the envelope of successive turns of the helix. To provide a uniform pitch, corresponding bends of the zig-zag are not necessarily aligned in the helical turns, because the distance between X's and Y's in successive turns is uniform.

FIG. 8 shows a vertical cross-section of ocean having a surface S and containing the present assembly E, a hydrophone H hanging from a float F, and three target submarines T_1 , T_2 , and T_3 embedded in the near-surface layers of the ocean. H, F, and E lie on approximately the same vertical line. Because T_1 , T_2 , and T_3 are situated at different distances from E, they will be in the path of sound of different frequencies. T_1 , the target closest to E, will be irradiated by sound of frequency f_1 ; T_2 , further removed from E, will be irradiated by sound of a higher frequency, f_2 ; and T_3 , the furthest target, will be irradiated by sound of still higher frequency, f_3 .

FIG. 9 is a top view of the situation shown in FIG. 8, the float F not being shown, however, in order that the assembly E may be depicted. C_1 is a circle drawn in the surface layers of the ocean and designating those points in the ocean's surface which are irradiated by sound of frequency f_1 . T_1 therefore lies on the circle C_1 . Similarly, C_2 and C_3 are circles of larger radius and designating points irradiated by sound of frequencies f_2 and f_3 , respectively. T_2 and T_3 therefore lie on the circles C_2 and C_3 .

FIG. 10 is a top view of a section of ocean irradiated by the sound produced from the assembly E and containing a target T and a hydrophone H, E and H not lying on the same vertical line. C_1 , C_2 , and C_3 are circles drawn in the surface layers of the ocean and designating those points in the ocean's surface which are irradiated by sounds of frequencies f_1 , f_2 , and f_3 , respectively. If an echo of a target is received by the hydrophone H at time t after the explosion of the charge, then the target must lie somewhere on the curve L as well as on circle C_1 , C_2 , or C_3 . L represents the intersection of a plane containing the target with an ellipsoid of revolution having foci at E and H and equal sound travel times over the path EPH, where P is any point on the surface of the ellipsoid. If the frequency of the echo of the target is f_2 , then the target must also lie somewhere on circle C_2 . The circle C_2 and curve L intersect at two points. Therefore, the target must be located at one of these two positions.

A preferred method of displaying the data obtained in echo ranging employing the present assembly is shown in FIG. 11. The display shows the series of events occurring when the helical charge of the present assembly detonates in the direction of the ocean's surface and the energy is received on a hydrophone located above the charge in vertical alignment therewith. D identifies the pulse received directly from the

charge; S the reflection from the ocean's surface; B the bottom reflection; BS the bottom-surface reflection; and so on. The hydrophone output is fed to a number of filters, each having a different pass band with sharp cutoff frequencies, which 5 separate the output into frequency bands covering the range of frequencies emitted by the charge. The data are displayed in a variable-density frequency-time presentation, the density being proportional to the amplitude of the energy in any given frequency band. Since the hydrophone is located above the assembly, the direct pulse is composed of high-frequency energy which is located at D on the display at maximum frequency and zero time. Reverberations S, SB, etc. which also appear on the upper part of the display, are the result of specular reflection and scattering from the surface and bottom of the ocean of the signal originally emitted by the charge in the upward direction. Conversely, pulses which leave the charge in a downward direction cause specular reflections and scatterings from the bottom and surface of the ocean of the signal originally emitted by the charge in the downward direction, 10 and have their frequency located on the lower part of the display. The target echo P is distinguished from biological noise M and N by its predicted frequency content and relatively short duration, the latter being determined by the emitted 15 pulse length and expected target size.

Curve F in FIG. 11 is a fiducial line on the presentation which shows the locus of the expected echo locations, this line being determined by the frequency distribution of the charge, the two-way travel time of the echo, the charge and 20 hydrophone depths, and refraction effects. Events Q and R represent countermeasure efforts taken by a target submarine. For event Q the submarine has recorded the initial pulse and played it back at a later time to give an erroneous range. This event, although it has the character of event P, is distinguishable 25 from it by the fact that it does not lie on the curve F. Event R is a different countermeasure attempt made by a target submarine. In this case, some time after the submarine has heard the direct pulse emitted by the helical charge it has simulated a broad-band echo of the type produced by conventional explosive charges. This countermeasure effort is distinguishable 30 by its broad band spectrum.

As is shown in FIGS. 8, 9, and 10, the frequency of the sound emitted toward the surface layers of the ocean by the detonation of the helical explosive charge in the present assembly varies with the distance of the irradiated surface area from the charge. The frequency irradiating the surface layers increases with time when the charge is initiated at the top, and this frequency decreases with time when the charge is initiated at the bottom. Therefore, in an echo ranging method employing the present assembly a target may be located by the use of time-dependent selection of the sound recorded from the receiver, i.e., by filtering the sound so as to separate only certain frequencies at one time interval after production of the 35 sonic pulse sequence, and to separate different frequencies at subsequent regular time intervals. The frequencies to be separated will be determined by a knowledge of the frequency characteristics of the sonic pulse sequence produced by the charge. When an expected frequency is received, the target 40 can be located by a knowledge of the angle at which such a frequency is emitted by the charge and by measurement of the time interval between emission of the pulse and reception of the echo. As is seen from FIG. 8, the target can be located on a circle when the hydrophone and pulse-producing assembly are positioned on the same vertical line. In the embodiment shown 45 in FIG. 10, in which there is horizontal displacement between the positions of the hydrophone and the helical charge in the ocean, the filtering of the sound with time can be used to locate the target at two possible positions, i.e., at the two intersections of curve L with the circle designating the echo frequency f_2 . The embodiment shown in FIG. 10 is particularly 50 advantageous in that it results in a reduction of back-scattered energy which may arrive at the same time and frequency as the echo pulse when the charge and hydrophone are on the same vertical line.

The echo ranging assembly of this invention contains a linear charge of detonating explosive arrayed in the form of a helix whose pitch, P , satisfies the relationship

$$P \leq 0.75 \times \frac{C}{D} \times L$$

where D is the detonation velocity of the explosive, L is the length of explosive in each turn of the helix, and C is the velocity of sound in sea water. The pitch, P , is the axial distance between corresponding points on the upper (or lower) boundary lines at the periphery of the linear charge (or on an imaginary envelope enclosing a zig-zag charge) in successive helical turns, as defined more specifically with reference to FIGS. 1 and 7. The length of the turn, L , is the length of explosive connecting these corresponding points. The detonation velocity of the explosive used and the length of each turn of the helix determine the frequency range of the pulse sequence produced and thus are selected on the basis of the frequencies desired. For any combination of D and L , the pitch, P , of the helix satisfies the above relationship. As a result, the component of the detonation velocity in the direction of the helical axis is no greater than three-fourths the speed of sound in the surrounding medium, i.e., sea water. This means that the time required for the detonation to travel from one end to the other of the helix is greater than the time required for sound in the ocean to travel the length of the axis of the helix. As a result, the spherical wave front from any segment of the helical charge will lie inside the wave front generated by any previously detonated segment. As the effective axial detonation velocity approaches the velocity of sound in water, or as P approaches $C/D \times L$, the duration of the pulse emitted in the direction of travel of the detonation approaches zero and the amplitude of this pulse becomes very large. This circumstance is to be avoided, because very strong pulses sent in a vertical direction will rarely produce submarine echoes and will always increase the reverberation interference. In the case in which the effective axial detonation velocity exceeds the velocity of sound in the surrounding water, there will always exist certain directions from the assembly where the pulses will superimpose to form such a single pulse having high energy and a very wide band spectrum which is not amenable to the narrow-band filtering technique. Therefore, sonic sources for which P is greater than $0.75 \times C/D \times L$ are not useful when narrow-band filtering is employed.

The helical explosive charge used in the assembly of the present invention can be made from any detonating explosive which will detonate reliably, when submerged, at a velocity equal to or greater than the velocity of sound in water, and consequently at a velocity in the range of 1,500 to 10,000 meters per second. Illustrative of the types of explosive charges which can be used to make the helical charge are "-Primacord," comprising a core of explosive surrounded by a nonexplosive sheath; and flexible, self-supporting cords or tapes obtained by extruding an explosive composition. The cross-sectional configuration of the length of explosive used in the helical charge is not critical and may be, for example, circular, semicircular, square, rectangular, oval, or flattened oval. The cord or tape should be capable of reliably supporting a detonation at the hydrostatic pressure existing at the desired detonation depth, which will generally be in the range of 5-2,000 fathoms.

The required minimum number of turns in the helix will vary according to the severity of reverberation conditions in a given area, but generally at least five turns will be necessary. We have found that charges having about 50 turns are sufficient for many applications although 5,000 or more turns may be used in special cases. The required minimum total mass of explosive in the charge will generally depend upon the level of ambient noise in the ocean and the required detection capability of the system, but will generally be 0.5-10 pounds.

Each helical turn has the same length of explosive, which will depend on the frequency range desired and the detonation velocity of the explosive. If, for example, the explosive

detonates at 7,000 meters per second and a frequency of 10,000 cycles per second is desired in the pulse sequence normal to the helical axis, each turn of the helix must be 0.7 meter long. That is, $L = D/f$, where f is the frequency. To provide long helical turns without imposing the necessity of an extremely large-diameter helix, the explosive cord or tape from which the helix is made may be in the form of a zig-zag, as is illustrated in FIG. 7. All of the bends in the zig-zag need not be uniform and corresponding bends need not be aligned in the helical turns, but the upper (or lower) boundary lines of the envelope of successive turns must be substantially equally spaced to give a uniform pitch. The cord or tape may be provided with the necessary zig-zag bends to result in the total length of explosive desired for a helical turn, and the zig-zag cord or tape may then be affixed to the collapsible tube to form a helix in a manner such that the length of cord or tape in each turn of the helix is the same.

As stated before, the pitch, or axial distance between corresponding points on the upper (or lower) boundaries of the envelopes of successive turns of the helix will be such as to satisfy the relationship

$$P \leq 0.75 \times \frac{C}{D} \times L,$$

The particular pitch used will depend on system requirements such as the speed, and size of the submarine target, the ambient noise level under which the system must operate, the required detection range, and the limitations on charge size and length imposed by the packaging requirements.

Because of the reflection characteristics of a submarine and the attenuation of sound in the ocean, the frequency range generally of interest in echo ranging is 50 to 20,000 cycles per second. Therefore, the length of the helical turn and the pitch will be such as to provide the desired frequencies in this range when an explosive having a detonation velocity in the above-specified range is used.

The frequency or period of the pulse sequence emitted at all angles from an assembly of a particular chosen geometry can be determined experimentally by measurement, or it can be calculated by the equation:

$$T = T_0 + (P/C) \cos \phi T$$

where T_0 is the period of the pulse sequence emanating in a normal direction from the assembly and is equal to L/D (L is the length of explosive in a helical turn and D is the detonation velocity of the explosive), P is the pitch of the helix, C is the velocity of sound in the sea, and T is the period of the pulse sequence emanating at some angle ϕ . ϕ is the angle between the direction from the array to an observer and the axial direction away from which the detonation travels.

The obtaining of the desired pulse sequence is dependent on the continuous propagation of detonation throughout all of the turns of the helical charge. Such continuous propagation will not be obtained if the detonation is propagated across the space between turns or if the detonation of a turn is physically disrupted by that of a previous turn. The distance between helical turns which will prevent continuous propagation will depend on the size of the helical charge and the form of the cord cross-section as well as on the sensitivity of the explosive. Generally, however, the charge should be so arrayed that the closest approach of explosive in successive turns of the helix is no less than the minimum cross-sectional dimension (S) of the linear charge. Usually S will be at least 1 millimeter. For the embodiment shown in FIG. 1, this spacing places an additional requirement on the pitch, P , i.e., that P should be no less than twice the minimum cross-sectional dimension of the linear charge. For the embodiment shown in FIG. 7, P should be no less than the total of (1) the minimum cross-sectional dimension of the linear explosive charge and (2) the width of the envelope bounding the zig-zag measured in an axial direction.

We have found that a preferred wave form and frequency spectrum can be obtained when the helical charge is designed in such manner that the amplitude of the pulses in a sequence is not constant. Such variation in amplitude can most readily

be achieved by having the amount of explosive per unit of length varied for different turns of the helix. A particularly desirable arrangement is one which will provide a sequence of pulses which vary in amplitude according to a Gaussian distribution, i.e., the amplitude of each successive pulse is increased uniformly to a maximum and thereafter decreased uniformly to the level of the first pulse. Such pulse emission will provide a reduction in side-lobe energy in a given frequency band. The foregoing can be achieved by forming the helix from a length of explosive in which the amount of explosive per unit of length is uniformly or step-wise varied from a minimum at each end to a maximum at the center. The rate of variation will be dependent upon the number of turns in the helix, the minimum amount of explosive per unit of length which will provide a pulse of sufficient amplitude for detection, and the maximum amount of explosive per unit of length that can be tolerated in the helix configuration. Further, a helical array of many turns may consist of a series of units of varying explosive loading.

Various types of support means can be used to maintain the desired helical configuration. In one embodiment, the tube 2 of FIG. 1 may be a rigid cardboard tube having the explosive charge attached to it by any convenient means, e.g., by stapling or by fitting into grooves in the cardboard. The lower end of the tube will be weighted to assure a vertical fall of the assembly when dropped into the water.

Inasmuch as the handling and transportation of such an assembly may prove difficult particularly when the helical charge is a large one, a convenient method of packaging the charge is to fashion tube 2 of FIG. 1 from a flexible plastic material, e.g., polyethylene. In this case, after affixing of the explosive charge onto the plastic, the tube will be collapsed for easy handling. The tube will be constricted at its upper end, and the lower end will be weighted. When the assembly is dropped into the water, the entry of water into the tube will open the tube into its expanded position.

In an alternate packaging means, the tube 2 of FIG. 1 may be eliminated, and the helical charge may be affixed to a wire of spring steel of the desired pitch.

The detonation of the helical explosive charge is initiated by an initiator attached to one end of the charge. The means for actuating the initiator is self-contained in the assembly and requires no connection with a vessel. Various initiators of this kind are known, for example, those which are actuated by the pressure of the water when a preselected depth is reached, e.g., the initiator described in U.S. Pat. No. 2,726,602. Alternatively, a timing device may be used as the actuating means.

The end from which the charge is initiated is optional, both bottom- and top-initiation providing the necessary Doppler effect.

Although the utility of the present assembly has been illustrated for echo ranging systems in which there is a vertical separation between the helical explosive charge and the expected depth of the target, the assembly can also be used in situations in which the charge is placed shallow in the ocean, i.e., at approximately the same depth as an expected target. In such situations, the system of time-dependent selection of the frequencies is effective and, in addition, if the horizontal distance between the charge and the target is not great, the variation in frequency will provide a determination of the depth of the target. However, at long ranges the frequency beam becomes sufficiently broad so that very little indication of depth of the target can be detected.

The time-dependent selection which may be used to advantage in conjunction with the assembly of this invention to determine the location of a submarine is also advantageous in that it provides a certain degree of immunity to countermeasures which might be taken by the submarine to escape detection. In conventional systems, the locating of the submarine is dependent on an accurate measure of the time interval between the reception of the direct pulse from the sonic source and the echo pulse from the reflected object, this time interval affording a measure of the additional distance

travelled by the echo pulse over the distance between the sensing device and the source. The submarine may interfere with such a system by sending out a pulse of the same frequency as that of the source. However, as is shown in FIG. 11, with the present assembly such a countermeasure would be ineffective inasmuch as it is used in conjunction with a time-dependent selection of frequencies, i.e., the expected frequency of the echo being received by the sensing device will change with time. Thus, the signal sent out by the submarine can be recognized as countermeasure noise because it will generally have the wrong frequency for its time of arrival.

Another advantageous feature of using the present assembly in a method of echo ranging over conventional methods is that, owing to the time-dependent selection of the frequencies, several of these assemblies may be employed at the same time without interfering with each other.

The invention has been described in detail in the foregoing. Many modifications will be apparent to those skilled in the art and will not require departure from the spirit of this invention. Accordingly, we intend to be limited only by the following claims.

We claim:

1. A sonic-pulse-producing assembly for use in underwater echo ranging which comprises

a. a linear charge of detonating explosive arrayed in the form of a helix having a uniform pitch, P , which satisfies the relationship

$$P \leq 0.75 \times \frac{C}{D} \times L$$

where D is the detonation velocity of said explosive, L is the length of explosive in each turn of said helix, and C is the velocity of sound in sea water, said linear charge being so arrayed that the closest approach of explosive in successive turns of said helix is no less than the minimum cross-sectional dimension of said linear charge;

b. supporting means adapted to maintain said explosive in said helical array; and

c. an initiator in initiating relationship to one end of said explosive, said initiator being adapted to be actuated by a self-contained actuating means when said assembly is at a predetermined depth in the ocean.

2. An assembly according to claim 1, wherein said initiator is actuated by a means responsive to hydrostatic pressure.

3. An assembly for producing a sequence of pressure pulses whose frequency varies in different directions from said assembly which comprises

a. a linear charge of detonating explosive arrayed in the form of a helix having a uniform pitch, P , which satisfies the relationship

$$P \leq 0.75 \times \frac{C}{D} \times L$$

where D is the detonation velocity of said explosive and lies within the range of 1,500 to 10,000 meters per second, C is the velocity of sound in sea water, and L is the length of explosive in each turn of said helix and is equal to D/f , where D is as defined above and f is a frequency within the range of 50 to 20,000 cycles per second, said linear charge being so arrayed that the closest approach of explosive in successive turns of said helix is no less than the minimum cross-sectional dimension of said linear charge;

b. supporting means adapted to maintain said explosive in said helical array; and

c. an initiator in initiating relationship to one end of said explosive, said initiator being adapted to be actuated by a self-contained actuating means when said assembly is at a predetermined depth in the ocean.

4. A sonic-pulse-producing assembly for use in underwater echo ranging which comprises

a. a collapsible tube of plastic film and having one constricted end and one fully open end;

- b. a linear charge of detonating explosive affixed to said tube in a manner such as to form a helix having a uniform pitch, P , which satisfies the relationship

$$P \leq 0.75 \times \frac{C}{D} \times L$$

5

where D is the detonation velocity of said explosive, L is the length of explosive in each turn of said helix, and C is the velocity of sound in sea water, said linear charge being so arrayed that the closest approach of explosive in successive turns of said helix is no less than the minimum cross-sectional dimension of said linear charge;

- c. an initiator in initiating relationship to one end of said explosive, said initiator being adapted to be actuated by a self-contained actuating means when said assembly is at a predetermined depth in the ocean; and
- d. a weight attached to said open end of said collapsible tube.

5. An assembly for producing a sequence of pressure pulses whose frequency varies in different directions from said assembly which comprises

- a. a linear charge of detonating explosive bent in the form of

- a zig-zag, said zig-zag explosive charge being arrayed in the form of a helix having a uniform pitch, P , which satisfies the relationship

$$P \leq 0.75 \times \frac{C}{D} \times L$$

5

where D is the detonation velocity of said explosive and lies within the range of 1,500 to 10,000 meters per second, C is velocity of sound in sea water, and L is the length of explosive in each turn of said helix and is equal to D/f , where D is as defined above and f is a frequency within the range of 50 to 20,000 cycles per second, said zig-zag charge being so arrayed that the closest approach of explosive in successive turns of said helix is no less than the minimum cross-sectional dimension of said linear charge;

- b. supporting means adapted to maintain said explosive in said helical array; and
- c. an initiator in initiating relationship to one end of said explosive, said initiator being adapted to be actuated by a self-contained actuating means when said assembly is at a predetermined depth in the ocean.
